UNITED STATES PATENT OFFICE.

HARRY H. BUCKLEY, OF CHICAGO, ILLINOIS, ASSIGNOR TO PITKIN & BROOKS, OF CHICAGO, ILLINOIS, A CORPORATION OF ILLINOIS.

DESIGN FOR A CUT-GLASS VESSEL.

No. 38,422.

Specification for Design.

Patented Jan. 22, 1907.

Application filed November 23, 1906. Serial No. 344,790. Term of patent 7 years.

To all whom it may concern:

Be it known that I, HARRY H. BUCKLEY, a citizen of the United States, residing at Chicago, in the county of Cook and State of Illinois, have invented a new, original, and ornamental Design for a Cut-Glass Vessel, of which the following is a specification, reference being had to the accompanying drawing, forming part thereof.

The figure is a side elevation of a glass vessel, showing my new design therein.

I claim—

The ornamental design for a cut-glass vessel, as shown.

HARRY H. BUCKLEY.
